(57) **CLAIM**

The ornamental design for a beverage container as shown and described.

DESCRIPTION

FIG. 1 is a perspective view of a first embodiment of a beverage container showing my new design;

FIG. 2 is a perspective upside down view thereof;

FIG. 3 is a front view thereof, and is identical to a back, a left, and a right side view thereof due to symmetry;

FIG. 4 is a top view thereof;

FIG. 5 is a bottom view thereof;

FIG. 6 is a perspective view of a second embodiment of the beverage container;

FIG. 7 is a perspective upside down view thereof;

FIG. 8 is a front view thereof, and is identical to a back, a left, and a right side view thereof due to symmetry;

FIG. 9 is a top view thereof; and,

FIG. 10 is a bottom view thereof.

The broken lines in the drawings depict portions of the beverage container that form no part of the claimed design.

1 Claim, 6 Drawing Sheets
